Nelson Howard

UNITED STATES PATENT OFFICE.

WILLIAM FOWLER, OF CINCINNATI, OHIO, ASSIGNOR TO UNITED SHOE MACHINERY CORPORATION, OF PATERSON, NEW JERSEY, A CORPORATION OF NEW JERSEY.

SOLE.

1,317,969.

Specification of Letters Patent.

Patented Oct. 7, 1919.

Original application filed October 15, 1915, Serial No. 56,093. Divided and this application filed August 28, 1918. Serial No. 251,741.

To all whom it may concern:

Be it known that I, WILLIAM FOWLER, a citizen of the United States, residing at Cincinnati, in the county of Hamilton and 5 State of Ohio, have invented certain Improvements in Soles, of which the following description, in connection with the accompanying drawings, is a specification, like reference characters on the drawings indicating 10 like parts in the several figures.

The present invention relates to the manufacture of boots and shoes and more particularly to the production of soles for use in the manufacture of shoes.

15 The invention is herein shown for purposes of illustration as embodied in an insole of the kind used in the manufacture of Goodyear welt shoes although it is to be understood that the invention is also applicable to the production of soles for shoes of other types.

20 Insoles of the kind used in making Goodyear welt shoes are ordinarily provided with a marginally extending shoulder by which 25 the shoe upper and the welt are secured to the insole and a feather which is the portion of the insole projecting beyond this shoulder and supporting the overlasted margin of the shoe upper. This feather is of substantially 30 the same cross-sectional thickness around the toe portion of the insole that it is along the adjacent forepart and the shank whereas the toe portion of a shoe upper and especially the portion which is lasted over 35 and supported by the feather of the insole is of an appreciably greater thickness than its adjacent portions because of the incorporation in the shoe upper of the additional toe stiffening materials. By reason of this 40 the welt of the shoe is necessarily seated on the overlasted portion of the shoe upper in a substantially higher plane relatively to the sewing shoulder about the toe of the shoe than throughout the rest of the shoe and consequently 45 considerable difficulty is experienced by the inseaming operator in sewing around the toe of the shoe. If the operator sews "high" on the sewing shoulder, thus locating the inseam substantially above its 50 base, a weak inseam results and subsequently when the sole is attached the toe portion of the sole is necessarily held out of the proper plane of the tread of the shoe

because of the height of the inseam at this point. On the other hand, if the height of 55 the sewing shoulder will not permit of its being sewed "high" the long stitch seam which is formed by sewing "full" will be exposed in the welt crease around the toe of the completed shoe and produce what is 60 termed in the trade a "grinning" toe which, of course, detracts from the neat appearance and salability of the shoe.

An object of the present invention is to produce an improved shoe sole which will 65 overcome the difficulties incident to the inseaming operation because of the increased thickness of the end portion of the shoe upper caused by the stiffening material, and which will result in superior shoemaking. 70

With this object in view the present invention contemplates the production of an improved sole for shoes in which the feather of an end portion of the sole is uniformly reduced in cross sectional thickness an 75 amount to compensate for the additional thickness of the upper stiffening material at the end portion of the shoe upper overlying the said reduced feather of the sole. The invention is herein illustrated as embodied in 80 an insole having a continuous sewing lip extending marginally of the insole and a feather projecting beyond the sewing lip. The feather of the insole is shown as reduced in thickness forwardly of a line substantially 85 coincident with the tip line by removing a skiving of uniform thickness from the upper or flesh side of the feather with any suitably adapted skiving machine although this reduction might well be obtained by compressing the feather of the insole at the toe. By reducing the cross sectional thickness of the feather of the insole about the toe portion, the plane of the overlasted margin of the shoe upper about the toe is substantially the 90 same throughout the shoe and it is similarly located relatively to the sewing rib or shoulder so that the upper and welt attaching seam may be properly located at the base of the shoulder about the toe portion of the 95 shoe with facility and precision.

Inasmuch as the object of the invention in one aspect is to increase the height of the sewing rib proportionately to the additional thickness of the shoe upper to be secured 100 thereto and this without causing the top of

- the sewing rib to project above adjacent portions of the rib, it is obviously sufficient to reduce that portion of the feather which is adjacent to the shoulder, leaving the entire edge portion of the sole of the original thickness. This procedure would, of course, be advantageous in the application of the invention to a sole for turn shoes. However, in an insole of the kind used in making Goodyear welt shoes, the thickness of the insole edge at the toe portion is more or less immaterial since it is adequately strengthened by the box toe materials and also it does not show in the finished shoe.
- Accordingly the feather of the sole is herein illustrated as being uniformly reduced throughout its entire width about the toe portion.

Other objects and features of the invention will be apparent from the following description when considered in connection with the accompanying drawings and the invention will then be defined in the appended claims.

Figure 1 is a perspective view of the forepart portion of the insole partly in section showing one manner in which the present invention has been carried out;

Fig. 2 is a transverse sectional view of one side of shoe illustrating the attachment of the upper and the welt to the shoulder of the insole rearwardly of the tip line of the shoe;

Fig. 3 is a similar view illustrating the attachment of the shoe upper and welt to the insole around the toe of the shoe.

The insole herein shown for convenience in illustrating the invention is of the "Economy-Gem" type which is used to a large extent in the manufacture of Goodyear welt shoes. This insole consists of a sole-shaped leather blank 2 having its upper marginal surface channeled so as to form an outer lip 4 and an inner channeled lip 6 from substantially the heel breast line on one side of the shoe around the shank and forepart to a point on the opposite side. The two channel lips 4 and 6 are turned upwardly and the surface of the blank is covered with a layer of reinforcing canvas 8 which extends across the upturned lips 4, 6 and on to the feather portion 10 of the sole projecting beyond the outer lip 4. The upstanding lips 4, 6, together with the canvas 8, constitute the shoulder or sewing rib to receive the stitches which attach the shoe upper and welt to the insole. The sewing shoulder, as shown, projects the same height above the feather portion 10 throughout and the channeling operation produces a feather of a uniform thickness. This structural relation of the feather 8 and the sewing shoulder 4, 6 of an insole being universally employed at the present time not only in insoles for the manufacture of Goodyear welt

shoes, but also in soles for shoes of other types, as for example turn shoes.

In accordance with the present invention, the insole is constructed and arranged to compensate for the additional thickness of the portion of the upper at the toe, which is lasted over the feather and against the sewing shoulder 4, 6 by reason of the toe stiffening element or toe box of the upper so as to cause the welt to lie in substantially the same plane about the toe portion of the shoe that it does through the forepart. This is herein accomplished by uniformly reducing the feather portion 10 of the insole around the toe an amount to compensate for the extra thickness of the toe stiffening material employed. As herein illustrated the reduced portion of the feather 10 extends from substantially the tip line at one side of the insole to a corresponding point on the opposite side as indicated at a, a, and conveniently this reduction is secured by removing from the upper surface of the feather 10 a skiving of substantially uniform thickness by the use of a suitable skiving machine. This reduction, however, could also be secured by compressing the material of the feather 10 of the insole about the toe. By thus reducing the thickness of the feather around the toe of the insole in the manner described, it will be seen that the depth of the shoulder or sewing rib 4, 6 is correspondingly increased an amount substantially equivalent to the additional thickness of the toe stiffening material where it is lasted over on to the feather and consequently the welt, when secured to the insole together with the upper, occupies the same position relatively to the shoulder and will lie in the same plane above the bottom of the last around the toe as it does along the forepart and shank.

In the use of the insole herein described, the portion of the shoe upper along the sides of the shoe is lasted over the feather 10 and formed against the shoulder 4, 6 in the usual manner as indicated in Fig. 2, the structural relation of the feather and the sewing rib being such that in the operation of attaching the welt 9 and upper 12 to the shoulder by stitches 14 they can be properly located at the base of the shoulder without undue manipulation of the shoe by the operator during the inseaming operation so as to draw the overlasted upper and the welt into the angle formed between the feather 10 and the outer wall of the sewing shoulder. In lasting the toe portion of the shoe the upper 12, together with the additional thickness of toe stiffening material indicated at 16, is lasted over the feather and against the shoulder 4, 6 in the same manner as along the sides. By reason of the reduction in the thickness of the feather 10, this overlasted portion of the upper, together with

- the welt, equals the thickness of the feather, the shoe upper and the welt along the sides of the shoe, as illustrated by the arrows *b c*, *c c*, Figs. 2 and 3. Thus the welt 9 occupies the same position relatively to the sewing shoulder at the toe that it does rearwardly thereof so that the inseam stitches 14 attaching the welt and upper can be as readily located at the base of the shoulder 4, 6.
- 10 While the inseam stitches about the toe are necessarily somewhat longer, by enabling them to be located at the base of the shoulder, the upper and welt are drawn into the angle in substantially the same manner as
- 15 along the sides of the shoe. Thus the difficulty of having the inseam stitches appear in the welt crease at the toe is entirely eliminated. Moreover, by causing the shoe upper and welt to be drawn into the larger angle
- 20 formed by reason of the greater height of the sewing shoulder a much shorter and consequently stronger inseam stitch is secured around the toe. Since the overlasted portion of the stiffening material fully offsets in
- 25 supporting utility the portion of the feather which is skived away, no impairment of the serviceability of the insole is occasioned by the reduction of the feather. It will be further noted that with the insole construction
- 30 herein described the inseam trimming operation can be performed more closely and uniformly without danger of cutting too deep into the inseam about the toe of the shoe because the welt and the inseam at the toe
- 35 project the same relative distance above the adjacent inner surface of the innersole throughout the entire shoe and as a further result the outsole can be seated upon a level surface and thus produce a flat tread surface
- 40 for the shoe. This latter feature is itself of considerable importance inasmuch as it eliminates many of the difficulties heretofore encountered by reason of the unevenness of the shoe bottom to receive the outsole and
- enables a better appearing shoe to be produced.
- Having thus described my invention, what I claim as new and desire to secure by Letters Patent is:
1. As an article of manufacture, a sole 50 for shoes in which the feather at the toe end portion of the sole is uniformly reduced in thickness throughout its surface an amount sufficient to compensate for the thickness of the upper stiffening material at the end portion 55 of the shoe upper in excess of its thickness along the sides of the shoe.
  2. As an article of manufacture, an insole for shoes comprising a blank provided with a marginal sewing rib and a feather located 60 outside the sewing rib and having the feather at the toe portion of the insole reduced in thickness relatively to the thickness of the adjacent portions of the feather an amount sufficient to compensate for the 65 thickness of the overlasted portion of the toe stiffening materials of a shoe upper.
  3. As an article of manufacture, an insole for shoes comprising a blank provided with a continuous sewing rib located a distance 70 in from the outer edge of the blank to form a feather for the sole and having the feather at the toe portion of the sole reduced in thickness relatively to the thickness of the adjacent portions of the feather an amount 75 sufficient to compensate for the thickness of the overlasted toe portion of a shoe upper which is in excess of the thickness of adjacent portions of a shoe upper.
  4. An insole having a toe portion 80 provided with a continuous lip, a substantial feather extending outside of said lip except at the toe and the feather substantially reduced in cross sectional thickness at the toe.
- In testimony whereof I have signed my 85 name to this specification.

WILLIAM FOWLER.
